SINK

Percy Howard Sterling, Mount Lebanon, Pa.
Application August 3, 1934, Serial No. 738,226

6 Claims. (Cl. 4—187)

This invention relates to a sink, lavatory, or the like.

In general, the invention has for an object to provide a sink of novel and improved construction, adapted to impart to the sink greater flexibility in use than the other prior sinks of which I am aware, and which at the same time enables the sink to be erected so as to occupy a minimum amount of the usable space of the room.

With this general object in view and such others as may hereinafter appear, the invention consists in the sink hereinafter described and particularly defined in the claims at the end of this specification.

In the drawing illustrating the preferred embodiment of the invention, Fig. 1 is a perspective of the preferred form of sink; Fig. 2 is a sectional view on the line 2—2 of Fig. 1; and Fig. 3 is a sectional view on the line 3—3 of Fig. 1.

0 In general, the present invention contemplates a novel construction of sink which is adapted to permit a plurality of operations such as washing and rinsing to be simultaneously performed in the sink in a convenient and practical manner. The construction of the present sink is such as to enable the same to be erected without occupying appreciably more space in the room than prior constructions of sinks of which I am aware.

Accordingly, a sink embodying the present invention is provided with two sink compartments arranged one in the rear of the other and each of which is provided with an individual drain to permit individual operations to be conveniently performed in each compartment. The sink is also provided with a splash board preferably formed integrally with the body of the sink, and in order to facilitate the conservation of room space in the room in which the sink is erected, the rear sink compartment is formed to extend a substantial distance in the rear of the general plane of the splash board. In the preferred embodiment of the invention, the splash board is formed integrally with the body of the sink and provided with a recess forming in effect an alcove 5 into which the rear sink compartment extends, and when the sink is erected upon the wall the recessed portion or alcove preferably is arranged to extend beyond the plane of the wall. The fittings such as the water inlet pipes, spigots and spouts may and preferably will be mounted upon the walls of the recessed portion or alcove.

Referring now to the drawing, which as above stated illustrates the preferred embodiment of the invention, 10 represents the body portion of the sink which is provided with two sink com-

partments 12, 14 extended one in the rear of the other. Each sink compartment 12, 14 is provided with an outlet or drain 15 whereby to permit individual operations to be independently performed in each compartment. The body portion of the sink is provided with a splash board 16 preferably formed integrally therewith and may also be provided with drain board or boards 18 of usual form and purpose.

In order to permit the conservation of space 10 occupied by the sink, the latter may and preferably will be erected upon the wall 20 with the rear compartment 14 of the sink extending a substantial distance rearwardly of the face of the wall and, in practice, it is preferred to form the splash 15 board with a recessed portion 22 forming in effect an alcove having side walls 24 and a top wall 26. The rear wall of the rear compartment 14 may and preferably will be extended to form the rear wall of the alcove, as illustrated in Fig. 1. 20

The sink may be provided with any usual or preferred form of fittings mounted upon the sink in any desired positions but it is preferred, as herein illustrated, to mount the fittings within the alcove or recessed portion 22. Such fittings 25 may include a swivel spout 27 mounted upon the upper wall 26 of the alcove in a position to be capable of supplying water to both compartments and also with the usual operating valves 28 controlling the supply of water to the pivoted spout 30 27. The rear compartment finds particular use as a drain compartment for dishes and other articles and to facilitate the rinsing thereof, a spray nozzle 29 may be provided upon one of the walls 24 of the alcove. 35

From the description thus far, and by reference to the drawing, it will be observed that the present construction of sink involving the two sink compartments arranged one in back of the other enables a plurality of operations to be 40 performed within the sink with more facility than has heretofore been possible with other constructions of sinks of which I am aware and, consequently, greatly increases the flexibility of use and general utility of the sink. The present construction of sink enables dishes to be washed in the front compartment and conveniently removed and placed into the rear compartment where they may be rinsed and permitted to drain without interfering with the washing of additional 45 dishes in the front compartment. In similar manner, other operations such as the washing and rinsing of vegetables may be conveniently performed, eliminating the necessity of the use of extraneous dishes and pans and enabling the 50 55

desired operations to be performed directly in the sink compartments themselves, while eliminating the necessity of walking in order to perform the different operations.

5. By arranging the compartments 12, 14 one in the rear of the other, it is possible to erect the sink upon the wall so that a substantial portion of the rear compartment projects rearwardly beyond the face of the wall and, as a result, the sink 10 may be provided with compartments of ample size for the purpose intended and at the same time may occupy no more of the room space than prior constructions of sinks. The location of the spout 28 and other fittings within the 15 alcove contributes to the ease with which the sink may be used with minimum obstructions and reducing to a minimum the liability of breakage of dishes, glassware and the like in the use of the sink, but it is not desired to limit the 20 invention in this respect.

As used herein, the term "sink" is intended to include kitchen and other sinks, lavatories, and the like.

While the preferred embodiment of the present 25 invention has been herein illustrated and described, it will be understood that the invention may be embodied in other forms within the scope of the following claims.

Having thus described the invention, what is 30 claimed is:—

1. As a new article of manufacture, a sink comprising two washing compartments arranged one in the rear of another and each of a substantial size and depth sufficient to enable washing operations to be performed therein, a splash board arranged with respect to the compartments so that the rear compartment extends at least partially in the rear of the general plane of the splash board.
2. As a new article of manufacture, a sink comprising two washing compartments arranged one in the rear of another and each of a substantial size and depth sufficient to enable washing operations to be performed therein, a splash board 45 provided with an alcove projecting rearwardly

of the general plane of the splash board, said rear sink compartment extending into said alcove and each compartment being provided with a drain outlet.

3. As a new article of manufacture, a sink having two washing compartments arranged one in the rear of the other and each of a substantial size and depth to enable washing operations to be performed therein, said sink being further provided with a splash board and with a substantially 10 horizontal drain board upon each side of the compartments, said splash board being recessed and having a portion of the recess extending downwardly to the bottom of the rear compartment, each compartment being provided with 15 a drain outlet.

4. A sink, said sink having two washing compartments arranged one in the rear of the other and each of a substantial size and depth sufficient to enable washing operations to be performed therein, a splash board having a recessed portion forming an alcove to be inserted into a wall in the rear of the face thereof, the rear compartment being at least partially received within said alcove, and fittings mounted upon the walls 20 of said recessed portion.

5. A sink, said sink having two washing compartments arranged one in the rear of the other and each of a substantial size and depth sufficient to enable washing operations to be performed therein, a splash board having a recessed portion forming an alcove to be inserted into a wall in the rear of the face thereof, and fittings located within said alcove to present minimum 30 obstruction in the use of the sink.

6. A sink, said sink having two washing compartments arranged one in the rear of the other, said washing compartments being of sufficient capacity to permit washing operations therein, two drain boards positioned adjacent to the said 40 washing compartments, and a splash board having a recessed portion forming an alcove to be inserted into a wall.

PERCY HOWARD STERLING. 45
